UNITED STATES PATENT OFFICE.

MARSHALL HENRY PEARSON, OF LEICESTER, ENGLAND, ASSIGNOR TO UNITED SHOE MACHINERY COMPANY, OF PATERSON, NEW JERSEY, A CORPORATION OF NEW JERSEY.

PUNCHING AND EYELETING MACHINE.

No. 918,694.

Specification of Letters Patent.

Patented April 20, 1909.

Application filed February 8, 1904. Serial No. 192,694.

To all whom it may concern:

Be it known that I, MARSHALL HENRY PEARSON, a subject of the King of Great Britain, residing at Leicester, in the county of Leicester, England, have invented certain Improvements in Punching and Eyeleting Machines, of which the following description, in connection with the accompanying drawings, is a specification, like reference characters on the drawings indicating like parts in the several figures.

This invention relates to eyeleting machines, and has for its object to provide a novel work-sustaining means which is movable relatively to a rigidly sustained lower eyelet-setting device for the purpose of stripping the stock from said device to enable the stock to be fed. The movable work-sustaining means may be elevated and depressed positively, or said work-sustaining means may be maintained normally in an elevated position by yielding means and depressed intermittently by a punch, presser foot, or other movable part.

In some types of eyeleting machines in common use the stock is fed either by means of the punch, which is moved laterally after it has penetrated the stock for forming an eyelet hole, or by means of the lower eyelet-setting device, which is moved laterally after the eyelet has been set and while the end of the setting device is still in engagement with the eyelet. In machines having a punch feed it is necessary at each operation of the machine to depress the lower eyelet-setting device for stripping the eyeleted stock therefrom, so that the stock may be fed. This also is necessary in machines in which the stock is fed by the lower eyelet-setting device, since it is necessary to strip the stock from said device to enable the latter to return to its normal position after feeding the stock. In both of these types of machines a great deal of complex mechanism is required for depressing the lower eyelet-setting device and for sustaining said device with sufficient rigidity to prevent it from yielding when the upper eyelet-setting device is actuated for setting an eyelet in the stock. To overcome these disadvantages I have provided a rigidly sustained lower eyelet-setting device and work-sustaining means which is movable relatively to the lower eyelet-setting device for stripping the stock therefrom to permit it to be fed. Means are

also provided for rigidly sustaining the anvil or punch plate during the punching operation.

The invention is herein shown as embodied in various forms, and in one form the movable work-sustaining means comprises a plate having a shank projecting into an opening in the end of the horn, the lower end of the shank being connected to mechanism for elevating and depressing the plate. In another form, the work-sustaining plate is shown as yieldingly sustained by means of a spring or friction device, and is adapted to be depressed by a punch or presser foot. The anvil or punch plate may be carried by the movable work-sustaining plate, in which case a portion of the horn acts as an abutment on which the sustaining plate rests during the punching operation, as shown in some forms of the invention, or the anvil may be fastened directly to the horn, as shown in other forms.

In the drawings, Figure 1 is a front elevation of a portion of a punching and eyeleting machine of common construction in which the lower eyelet-setting device moves laterally for feeding the stock; Fig. 2 is a detail view in side elevation looking from the right of Fig. 1, and shows the feed arm in which the lower eyelet-setting device is mounted; Fig. 3 is a sectional view taken on the line x-x of Fig. 4; Fig. 4 is a plan view showing the stock-sustaining plate, anvil, a portion of the horn, and the feed arm, which carries the lower eyelet-setting device; Fig. 5 is a sectional view of a modification of the form shown in Fig. 3; Fig. 6 is a sectional view of another form of the invention, in which the stock-sustaining plate is yieldingly supported and the lower setting device is mounted in the horn, the stock being fed by a laterally moving punch, not shown; Fig. 7 is a plan view of the parts shown in Fig. 6; Fig. 8 is an end elevation of the parts shown in Fig. 6; Fig. 9 is a detail view of the rotatable adjusting stud; Fig. 10 represents a modification of the form shown in Fig. 6; Fig. 11 is a front elevation, partly in section, of another form of the invention, the section being taken on line x-x of Fig. 12; Fig. 12 is a view, partly in section, as seen from the right of Fig. 11, the section being indicated by the line y-y of Fig. 11; and Fig. 13 is a plan view of the movable sustaining plate and stationary anvil shown in Fig. 11.

Fig. 1 of the drawings represents a portion of an ordinary punching and eyeleting machine in which 2 designates the base and 3 the horn rigidly attached thereto. A standard 4 projects upwardly from the base and carries the head in which the punch 5, upper eyelet-setting device 6, and raceway 7 are mounted. The horn at its upper end is provided with an upwardly extending part 8 which affords a rigid support for the work-sustaining plate 10 when it is in its lowermost position, and said plate has a shank 12 which is slidably mounted in an opening formed in the extended part 8 of the horn, as shown in Fig. 3. The lower end of the shank 12 is connected to any suitable actuating mechanism for elevating the work-sustaining plate to remove the eyeleted stock from engagement with the lower eyelet-setting device, as hereinafter described. The sustaining plate 10 is provided with a T-shaped slot in which an anvil or punch plate 13 is movably mounted, said anvil having an opening or passageway 14 into which the lower setting device 16 projects.

Pivotedly mounted in lugs 18 projecting from the standard is a feed arm 20 having an extended part 22 which projects into an opening in the standard, as shown in Fig. 2, said extended part being adapted to be engaged by suitable means for imparting an oscillating movement to the feed arm. Mounted in the outer end of the feed arm is the lower setting device 16 which is provided with a screw-threaded portion 23 in engagement with a corresponding screw-threaded portion formed in a downwardly extending part of the feed arm, which part travels in a slot 24 formed in the upper end of the horn adjacent to the extended part 8. On the threaded end of the setting device is a lock nut 25 which contacts with the under side of the feed arm and holds said device in position after it has been adjusted, the upper end of the setting device being flush with the surface of the anvil or punch plate when the work-sustaining plate is in its elevated position. A portion of the lower edge of the feed arm rests on the horn, as shown in Figs. 2 and 4, and affords a rigid support for the lower setting device when the upper setting device is actuated to upset the shank of an eyelet to secure it in the stock.

The operation of the mechanism just described is as follows: The feed arm normally occupies the position shown in full lines in Fig. 3 and the sustaining plate normally rests upon the extended part 8 of the horn, which affords a rigid support for said plate when the punch operates. The acting end of the lower setting device projects through the passageway in the anvil 13, and the stock, which it will be supposed has been provided with a hole to receive an eyelet, is placed on the sustaining plate with the hole

in alignment with the eyelet-setting devices. The upper setting device and punch are then actuated, and in the downward movement of said setting device an eyelet is removed from the raceway, inserted in the stock, and the end of the shank of the eyelet is upset by the coöperation of the upper and lower setting devices. The feed arm is then moved laterally into the position shown in dotted lines in Fig. 3, and as the end of the lower setting device is still in engagement with the eyelet that has just been set, the stock will be fed forward into position to receive the next eyelet. The end of the sustaining plate is bifurcated at 26 to permit lateral movement of the lower setting device, and as said device projects upwardly through the opening in the anvil 13 said anvil will be moved laterally with the feed arm. When the feed arm has arrived at the end of its lateral movement, as shown in dotted lines in Fig. 3, the sustaining plate is elevated into the position shown in Figs. 2 and 3, thereby stripping the eyeleted stock from the lower setting device, so that the feed arm and anvil can be returned to their normal positions, the lower setting device projecting into the passageway in the anvil, but not projecting above the surface thereof while the sustaining plate is in its elevated position. After the feed arm has been moved back to its normal position the sustaining plate is then lowered to again rest on the projecting part 8 of the horn, and the same operations are repeated for inserting other eyelets.

Fig. 5 illustrates a modification of the mechanism shown in Figs. 1 to 4, inclusive, and in this form the feed arm 20 carries the work-sustaining plate 11 and also the lower setting device 16, the extended part 9 of the horn being provided with a stationary anvil 27 on which the punch acts.

In Figs. 6 to 9, inclusive, is shown a modified form of the invention which is to be used in combination with a machine in which the punch moves laterally for feeding the stock, as in the machine shown and described in United States Letters Patent No. 478,759, dated July 12, 1892. In this form of the invention the upper end of the horn is provided with a depression or recess 30 to receive the sustaining plate 10*, and projecting downwardly from said plate into a vertical opening 32 formed in the horn is a hollow shank 12*. A coiled spring 34 is confined within the hollow shank and bears at one end against the top wall of the hole in the shank and at its other end against a retaining plate 36 which is detachably secured to the horn and forms a closure for the opening in which the shank of the sustaining plate moves. The spring holds the sustaining plate normally elevated, as shown in Fig. 6, so that the end of the lower setting device will not project above the surface of said

plate, and the elevated position of the plate is controlled by an adjusting device comprising a rotatable stud 37 which is mounted in a horizontal opening in the horn, as shown 5 in Fig. 6. The stud is provided with a shoulder 38 formed by cutting away a portion of the stud, and this shoulder is adapted to engage the lower edge of a recess 40 formed in the side of the shank 12^a to there- 10 by limit the upward movement of the sustaining plate. The stud is also provided with a slot 41 into which the end of an adjusting screw 42 projects, said screw being mounted in the horn and provided with a 15 lock nut 44 for holding it in adjusted position. The side walls of the slot in the stud are engaged by the screw 42, which prevents the stud from being moved transversely of the horn, and the end of the screw is rounded 20 and bears against the curved bottom wall 45 of the slot, so that by adjusting said screw the position of the shoulder 38 on the stud may be varied and the elevated position of the work-sustaining plate may be controlled. The sustaining plate 10^a is provided with an anvil or punch plate 46 on which the punch operates, and is also provided with an opening or passageway 14^a into which the lower setting device 16^a extends. The lower setting device 16^a is mounted in an opening in the horn, and at 25 its lower end is engaged by an adjusting screw 48 that enables the elevated position of the device to be varied, and a locking screw 50 which engages the side of said setting device holds it in adjusted position. Detachably secured to the outer end of the sustaining plate is a plate 52 which prevents dust from collecting in the space between the lower surface of the sustaining plate and the bottom of the depression or recess 30.

In the operation of this form of the invention the stock, which has been provided with an eyelet hole, is placed on the sustaining plate with the eyelet hole in alignment with a 35 eyelet-setting device. An eyelet having been set the punch descends to form a hole in the stock and forces the plate 10^a downwardly against the stress of the spring 34. After the sustaining plate has reached the limit of its downward movement, which in this form is the bottom of the depression 30, the punch, is thereafter retracted slightly and is moved laterally for feeding the stock, 45 the sustaining plate moving upwardly as the punch is retracted, so as to hold the stock in engagement with the end of the punch, and also to strip the eyeleted stock from the lower setting device. When the punch arrives at the end of its lateral movement the 50 usual presser foot 60, such as shown in Figs. 11 and 12, is actuated for stripping the stock from the punch and for forcing the sustaining plate downwardly to expose the end of the

lower setting device. The punch is then re- 65 tracted and moved back to starting position and the upper setting device is moved downwardly, said device removing an eyelet from the raceway, inserting it in the hole in the stock, and forcing it into engagement with 70 the lower set which upsets the end of the shank of the eyelet to fasten it to the stock.

Fig. 10 represents a modification of the form shown in Figs. 6, 7, 8 and 9, and in this construction, instead of yieldingly maintaining the stock-sustaining plate 10^a normally in its elevated position, means are provided for positively moving said plate upwardly to strip the eyeleted stock from the lower setting device and to hold the stock in engagement with the punch during the feeding movement, said means comprising a rod 61 connected at its upper end to the shank 12^a and at its lower end to suitable actuating mechanism, not shown. Frictional means 85 comprising a spring-pressed plunger 64 is adapted to bear against the surface of the shank 12^a for holding the sustaining plate elevated until it is again depressed by the action of the presser foot. 90

Another form of the invention is illustrated in Figs. 11, 12 and 13, and in this form a stationary anvil 70 is fastened to the horn by screw 71, said anvil being surrounded by a movable stock-sustaining plate 10^b provided with an opening or passageway 14^b to receive the lower setting device 16^b and also having a hollow shank 12^b which moves in a vertical opening formed in the horn. The shank incloses a spring 34^b which holds the plate 10^b normally elevated, as in the construction shown in Fig. 6, the operation of both of these forms being substantially the same, except that in the form shown in Fig. 11 the punch does not contact with the anvil 100 during the lateral movement of the punch. The punch 52 which is used in this form of the invention is provided with a downwardly projecting lug 72 which engages the plate 10^b when the punch moves downwardly, so as to 110 depress said plate flush with the surface of the anvil. 105

Having described my invention what I claim as new and desire to secure by Letters Patent of the United States, is:—

1. In a machine of the class described, a lower setting device supported rigidly against movement in the direction of the force applied in the act of setting; mechanism for feeding the stock; and movable stock-sustaining means arranged to co-operate with the feeding mechanism for facilitating the feed of the stock. 115

2. In a machine of the class described, a lower setting device supported rigidly against movement in the direction of the force applied in the act of setting; mechanism for feeding the stock; stock-sustaining means 120

125

arranged for movement transverse to the direction of feed of the stock; and means for moving the stock-sustaining means.

3. In a machine of the class described, a rigidly supported lower setting device; a stock-sustaining plate arranged to be moved for stripping stock from said device; and means for causing relative movement of said device and the stock after the latter has been stripped from the former.

4. In a machine of the class described, a rigidly supported lower setting device; a stock-sustaining plate movable between predetermined limits for stripping the stock from said device and for permitting said device to engage the stock; means for varying the position of said device relative to said predetermined limits of movement of said plate; and means for feeding the stock when said plate is at one of the limits of its movement.

5. In a punching and eyeleting machine, a lower setting device supported rigidly against movement in the direction of the force applied in the act of setting; stock-sustaining means arranged to be moved for moving the stock; a punch; and a cooperating anvil.

6. In a punching and eyeleting machine, a movable work-sustaining plate, a feed arm, a lower eyelet-setting device mounted in the feed arm, and means for rigidly supporting the work-sustaining plate and feed arm during the punching and eyeleting operations.

35 7. In a machine of the class described, a stock-sustaining plate provided with a mov-

able anvil; a feed arm; a setting device mounted on the feed arm and arranged to engage the anvil; and means for moving the stock-sustaining plate and anvil relatively to said setting device.

8. In a machine of the class described, the combination of a rigidly supported lower setting device, means for moving said setting device to feed the stock, and a stock-sustaining means movable to strip the stock from said setting device to allow the return of said setting device.

9. In a machine of the class described, the combination of a rigidly supported lower setting device, means for moving said setting device laterally to feed the stock, and a stock-sustaining means movable in a direction transverse to the feeding movement of said setting device for stripping the stock from said setting device, and means for moving said stock-sustaining means.

10. In a punching and eyeleting machine, a rigidly supported lower setting device; stock-sustaining means arranged to be moved for moving the stock; a punch and a cooperating anvil; said stock-sustaining means and anvil cooperating to sustain the stock during the setting operation.

In testimony whereof I have signed my name to this specification in the presence of two subscribing witnesses.

MARSHALL HENRY PEARSON.
